UNITED STATES PATENT OFFICE.

BENJAMIN J. BASKERVILLE, OF JOLIET, ILLINOIS.

WATER-MOTOR.

1,009,014.

Specification of Letters Patent. Patented Nov. 14, 1911.

Application filed April 13, 1911. Serial No. 620,933.

To all whom it may concern:

Be it known that I, BENJAMIN J. BASKERVILLE, a citizen of the United States, residing at Joliet, in the county of Will and State 5 of Illinois, have invented a new and useful Water-Motor, of which the following is a specification.

My invention is termed a water motor, because the motor or engine is mainly intended 10 to be operated by water-pressure, while it can be operated with steam or compressed air.

The use of my invention as a water motor is mainly for the purpose of connection with 15 a pump for raising water from cisterns and filling pipes that may be extended to any part of a building, and when the pressure in the cistern or soft water pipes is equal to the pressure of the water in the motor, drawn 20 from some city water main, the motor will stop. When water is drawn from the cistern pipes by means of faucets, the motor will be put in motion until the water drawn 25 is replaced and the balancing pressure in the cistern pipes restored, when the motor will again automatically stop, the motor being automatically put in motion by opening a cistern pipe faucet, and automatically 30 stopped when the cistern water drawn is replaced in the cistern pipes.

I am aware that there are motors used for distributing water as above indicated, but owing to their structure there is leakage 35 through such motors when stopped, which is a great defect and which proves very expensive, especially, where the water used is measured by water meters.

Owing to the novel construction of valves and the position of ports in my invention, 40 no water can pass through it when at rest, assuming the motor to be carefully constructed according to a correct working drawing. Of course, when used for other purposes than raising water out of a cistern 45 or other reservoir, the motor is stopped and started by the use of a stop valve in the connection pipe.

I attain these objects by the mechanism 50 illustrated in the accompanying drawing, in

Figure 1 is a sectional view on line E—F

Fig. 2. Fig. 2 is a sectional view on line A—B—C—D Fig. 1. Fig. 3 is a section of the valve chest cover.

Casing 1 is the outer cover of the entire 55 motor. With the valves in the position shown in the drawing, water is introduced through the connecting pipe 27 into chamber 23 which opens into chambers containing the ports 7 and 11, which chambers and 60 ports are reciprocal, port 7 being neutral and port 11 active; then water passes through ports 11, 12 and 17 and behind piston 3 and forces the same to the left. As pistons 2 and 3 are both connected to the 65 piston rod 4, the water in front of piston 2 is forced through ports 16, 6, 18, 9, right 14 and exhaust 26. After the piston 3, in its stroke to the left, passes port 15, the water passes through ports 15, 10 and 19 to 70 the right end of valve 5 and forces the latter to the left until bumper 30 reaches casing 1. Chambers 24 and 25 are reciprocal air chambers. Were it not for air-chamber 25, valve 5 in passing to the left, would stop after 75 closing port 12, but the compressed air in said chamber forces down enough water to complete the left stroke. As valve 5 is passing to the left, the water in front of same passes out through ports 18, 9, left 14 and 80 exhaust 26, and thus makes a complete reversal of water pressure. Each port and chamber in the right side of the motor is reciprocal with the one in a corresponding position in the left side, not counting the inlet 27 and exhaust 26 which are exactly in 85 the center.

28 represents the piston chamber and 29, the valve chamber.

The chambers 24 and 25, Fig. 3, open, re- 90 spectively, into chambers 31 and 32, Fig. 1. Water in chamber 23, Fig. 3, alternately passes in to chambers 33 and 34, Fig. 1, one end of chamber 23 being closed while other end is open.

95 What I claim is—

The water-motor; consisting of the casing 1 inclosing the valve chamber 39, the piston chamber 28 and chambers between; the valve 5 movable in said chamber 29 by means of 100 the alternate reception and expulsion of water through ports on the one side acting

alternately with ports in like position on the other side; the valve chest cover connected to casing 1 over said intermediate chambers; the air chambers 24 and 25 forming a part 5 of said cover; the pistons 2 and 3 connected to piston rod 4 and movable in chamber 28, by means of the alternate intake and expul-

sion of water through said alternately acting ports, all substantially as illustrated and set forth.

BENJAMIN J. BASKERVILLE.
